UNITED STATES PATENT OFFICE.

FREDRICK W. FRESE, OF SPOKANE, WASHINGTON.

INTERNAL-COMBUSTION ENGINE.

Application filed March 2, 1925. Serial No. 12,562.

The present invention relates to improvements in internal combustion engines of the multiple piston type wherein two working pistons move simultaneously in opposite directions in a single cylinder or cylindrical structure composed of two working cylinders arranged tandem with a combustion chamber or space between the pistons.

The gases resulting from combustion of the liquid fuel within the combustion chamber as they expand act with equal pressure upon both pistons and transmit power through the pistons to the main driving or crank shaft of the engine or motor. The invention comprises a plurality of units as above indicated arranged in parallelism, and in the drawings I have illustrated a four cylinder unit in a motor, as an exemplification of my invention.

By the utilization of my invention in an internal combustion engine a maximum of power is derived from the use of a minimum quantity of fuel thus economizing in fuel consumption and enhancing the power of the motor.

While the motor may be utilized in horizontal or other positions, I have shown it in vertical position for convenience of illustration and description.

The invention consists in certain novel combinations and arrangements of parts as will hereinafter be more fully set forth and claimed.

In the accompanying drawings I have illustrated one complete example of the physical embodiment of my invention wherein the parts are combined and arranged in accordance with the best mode I have thus far devised for the practical application of the principles of my invention.

Figure 1 is a vertical longitudinal sectional view showing a four cylinder engine embodying the principles of my invention, the pairs of pistons in the four cylinders showing the four different relations of a single pair of pistons in a single piston.

Figure 2 is a horizontal transverse sectional detail view showing a portion of the motor with exhaust and intake manifolds connected to the cylinders.

Figure 3 is an enlarged detail sectional view at right angles to Figure 1 and at line 3-3 of Figure 1.

Figure 4 is an enlarged detail sectional view of one of the valve-pistons showing

also its connecting rod and cam shaft in the form of a crank shaft.

Figure 5 is a detail sectional view of the piston of Figure 4 as seen at right angles thereto.

In the preferred form of the invention as illustrated in the drawings I employ a sectional engine case comprising an upper crank case 1, an intermediate block 2 and a lower crank case 3, which sections are detachably bolted or otherwise secured together to facilitate access to the several pistons and their connections.

A water jacket 4 is shown around the cylinder portion of the case between the crank cases for cooling purposes, and two crank shafts 5 and 6 are shown in Figure 1 journaled in parallel planes in their respective cases. Either of these shafts may be used to transmit power, but for convenience I have shown the crank of shaft 5 as a cam shaft for operating the valves of the pistons and shaft 6 as a driving or engine shaft with a balance or fly wheel 7 thereon. The usual cooling fan 8 may be driven from a belt 9 and pulley 10 on the crank shaft in customary manner.

The two shafts 5 and 6 are geared to revolve together through a drive gear 11 on the crank shaft 6 and gear 12 on the crank shaft 5 and an intermediate idle gear 13 is interposed between these gears as indicated in Figure 1. The gear 11 is one-half the diameter of the gear 12 giving a ratio of 2:1 to provide a two cycle operation of the cam shaft and upper part of the cylinders and a four cycle operation of the crank shaft and lower parts of the cylinders.

The four cylinders of the motor are designated 14 15 16 and 17 reading from the left in Figure 1, and as shown these cylinders are open at bottom and top and are formed of the three sections of the engine casing.

In each cylinder a pair of pistons are arranged in axial alinement. The opposed pistons are designated 18 and 19, 20 and 21, 22 and 23, and 24 and 25, in the respective cylinders and reading from left to right in Figure 1. The lower pistons have connecting rods 26 journaled to the crank at 27, and the upper pistons have connecting rods 28 connected with the cam shaft 5. The connections with the cam shaft are offset quarters and the connections of the rods to the crank shaft are offset at halves to insure

proper performance of the two cycles at the upper and lower portions of the engine.

The four lower pistons are of usual or standard construction, while the four upper 5 pistons complementary thereto are of specific construction for carrying out the principles of my invention.

In Figures 4 and 5 the construction of one of the valve-pistons or upper pistons is 10 illustrated, and as the other three are of similar construction, a description of one will suffice for all of them.

As seen in Figures 4 and 5 the hollow valve pistons are each fashioned with an 15 exhaust port 29 and an intake port 30 located in opposite side walls of the piston and at different transverse planes. The exhaust port is adapted to register with a complementary exhaust port 31 in the cylinder 20 and the intake port 30 is adapted to register with the intake port 32 of the cylinder receiving the fuel supply. Any standard form 25 of carburetor may be connected with the intake manifold 33 in Figure 2 which communicates with the several intake ports of the cylinders, and the exhaust manifold 34 is adapted to exhaust gases from the several 30 cylinders.

The intake port 30 to the piston opens to 35 a fuel supply chamber 35 in the piston and this chamber is fashioned with a valve seat 36 in the piston head for the intake valve 37.

An exhaust valve 38 adapted to seat in a 40 port 39 in the piston head controls passage 35 of gases of combustion to the exhaust chamber 40 with which the exhaust port 29 in the piston communicates.

Each of the intake and exhaust valves has 45 a stem as 41 and 42 which project upwardly 40 into the hollow wrist pin 43 of the piston and through a sleeve 44 for the pin. Springs 45 on the stems normally hold the 50 valves closed in their seats in the piston head.

The valve operating mechanism includes 55 a rod 46 for the intake and a valve rod 47 for the exhaust, one at each side of the connecting rod 28. These push rods are carried by the connecting rod but are slidable 60 relatively thereto and are supported in guide bosses 48 arranged in pairs at the sides of the connecting rod.

Each push rod carries a cam wheel 49 at 55 its outer end, and the crank of the shaft 5 is provided with a pair of cams 50 and 51 for co-action with the wheels of the intake and exhaust push rods respectively. As seen 60 in Figures 3, 4, and 5 the cam rods or push rods meet and contact with the valve stems of the two valves within the center of the hollow wrist pin, and the rods are intermittently actuated at the proper times to push the valve stems to open the valves. This 65 movement is actuated through the timing gears from the driving shaft and through

the crank shaft, cams thereon and the cam or push rods.

The fuel charge for combustion is admitted to the combustion chamber 52, formed between the opposing pistons in the cylinder, through the valve seat when the intake valve is opened by the cam action. A spark plug 53 (Fig. 3) of usual or standard form is employed to ignite the fuel charge in the combustion chamber. The spark plug is preferably located above the median line of the cylinder and toward the upper end thereof, and the fuel charge is compressed at a point between the two pistons when the lower piston is at the upper end of its up stroke and the valve piston on the half stroke, as in Figure 3 which shows the exhaust position in cylinder 17 and the firing position in cylinder 15.

In No. 1 cylinder at the left shown in 85 Figure 1 as 14 both the pistons are at the end of a stroke in the ends of the cylinders and spaced at their extreme positions for the expanding position.

As the engine is operated both pistons 90 move toward each other, the four cycle piston 19 traveling twice as fast as the two cycle or lower piston 18. The piston 19 therefore approaches piston 18 when the latter has made one half its stroke during the 95 time the piston 19 has made its full in-stroke, and the crank shaft 6 is on the dead center. This exhaust position is indicated 100 in cylinder 15, in Figure 1, which is exhausted.

The piston 19 then moves on its outstroke 105 making a full reach of its cylinder and piston 18 also reaches the end of the cylinder on its instroke, with the throw of both 105 shafts pointing downwardly as in cylinder 16. During this outstroke of the piston 18 a fuel charge has been drawn into the combustion chamber between the adjoining 110 heads of the pistons.

The compression stroke now takes place, 115 both pistons starting on an upstroke with the piston 18 moving more rapidly than piston 19 to compress the fuel charge. When piston 18 has completed its movement 115 piston 19 has made only a half stroke, the charge has been compressed and the pistons are in firing position for ignition of the charge by the spark plug. The combustion drives both pistons on an outstroke to expansion position of cylinder 14 and the cycle 120 is repeated.

In the exhaust position of the pistons of 125 Figure 3 in cylinder 15 the exhaust has taken place, valve 38 has closed and the exhaust port 29 of the piston is closed against port 31 in the cylinder wall, but intake valve 37 is about to open. The intake port 32 of the piston is in line with port 30 in the cylinder wall and on the outward stroke following the two ports register while 130

the valves remain closed, hence no action takes place through the ports.

The parts are so timed and arranged that compression and explosion take place when the crank pin 5 is at its full leverage, with its piston one half way on its outward stroke, and as the piston 20 reaches nearly the end of its stroke the piston 21 is on the full leverage of the crank pin 6.

10 The exhaust valve does not open against pressure of explosion when gas is fed to the combustion chamber due to the fact that the expansion stroke is longer than the intake stroke. Little, if any power is used in compressing the mixture as the compressed mixture is forced against the piston head 20 at the full leverage of the crank shaft by the piston 21 which at this time is near the end of its stroke with the crank shaft throw near 20 the dead center. This force applied against piston 20 by the full leverage of the crank shaft assists in operating the upper pistons through the movement of the timing gears.

The crank pin 6 and its bearings are lubricated in usual manner, while the crank shaft and its parts are lubricated with oil from the

lower crank case through exterior oil pipe 54 in Figure 3 which communicates with the oil ducts in the cam shaft as indicated at 55 in Figure 1, and a pump 56 in the lower 30 crank case is used to circulate the lubricant.

Having thus fully described my invention, what I claim as new and desire to secure by Letters Patent is:

In a valved piston construction, a hollow 35 wrist pin, a connecting rod connected thereto, said wrist pin having guide slots formed therein at opposed points and in registry on opposite sides of said connecting rod, valve stems disposed through certain 40 of the slots from the piston head, brackets projecting laterally from opposite sides of said connecting rod, push rods carried through said brackets for longitudinal movement relative to said connecting rod, said 45 push rods extending through other of the wrist pin slots to engage said valve stems within the wrist pin, and means on said push rods for timed operative engagement with an engine crank shaft. 50

In testimony whereof I affix my signature.

FREDRICK W. FRESE.
